UNITED STATES PATENT OFFICE.

ARTHUR EDWARD STROUD, OF LONG EATON, AND HAROLD FREDERICK SOAR, OF ALVASTON, ENGLAND, ASSIGNORS TO STROUDS TAPE MACHINES, LIMITED, OF LONG EATON, ENGLAND, A CORPORATION OF GREAT BRITAIN.

LOOM.

1,188,218.

Specification of Letters Patent. Patented June 20, 1916.

Application filed May 19, 1914. Serial No. 839,524.

To all whom it may concern:

Be it known that we, ARTHUR EDWARD STROUD and HAROLD FREDERICK SOAR, subjects of the King of Great Britain, and residents of Long Eaton and Alvaston, respectively, both in the county of Derby, England, have invented new and useful Improvements in Looms, of which the following is a specification.

10 This invention relates to improvements in narrow-ware looms in which a number of tapes, ribbons, and similar fabrics are simultaneously woven in parallel vertical planes, and has for its object improvements 15 in the construction and arrangement of the shuttle and reed carrying and actuating mechanisms, by and through which improvements the shuttles can be traversed through the sheds, or partly through the 20 sheds, during the time the reed is moving vertically, or, during a part of such time; also improvements in the means for taking up the work, and improvements in the general arrangement and construction of the 25 loom.

In the drawings:—Figure 1 is an end elevation of a vertical loom constructed according to this invention. Fig. 2 is a transverse section of the same. Fig. 3 is a part 30 transverse section of the loom to an enlarged scale showing the reed in the beat up position. Fig. 4 is a part sectional front elevation of Fig. 3. Fig. 5 is a front elevation of the shuttle. Fig. 6 is an elevation 35 of a work take-up roller, and Fig. 7 illustrates a modified form of shuttle and shuttle guides.

The loom shown in the drawings is provided with a central frame which includes 40 the front angle rail 1 and the back angle rail 2. The ends of these rails are connected by brackets 3, Fig. 1, at both ends of the loom to vertical rods 4 which are fitted to slide in fixed guides 5 and are rigidly connected together by cross bars 6 and 7. Between the cross bar 7 and the lower guides 5 there are springs 8 by which the weight of the central frame and its connected parts is wholly or partially balanced. The central frame is driven at both ends to reciprocate vertically by crank pins 9 on the driving shaft 10, such cranks being coupled to the cross bars 7 by links 11, levers 12 and 13, and links 14, the parts being so arranged

that when the levers 13 are approximately 55 vertical the central frame is at, or near, its lowest position and practically rests in this position for a short period of time.

Mounted upon the rails 1 and 2 there are brackets 15 which are grooved at the sides 60 to form guides for the shuttle 16, and in connection with each rail there is a shaft 17, carried in bearings which are attached to the rails, and each shaft is provided with toothed pinions 18 by which the shuttles are 65 traversed to and fro through the sheds. The shafts 17 at both ends of the loom, are fitted with driving pinions 19 and are oscillated by quadrants 20 which are mounted upon axles carried by the cross bars 6. 70 Each quadrant is provided with a driving stud 21, which is adjustably attached to the quadrant, and engages with a slot in the end of a lever 22 which is pivotally mounted upon an axle 23 carried by the standard 24. 75 The lever 22 is driven from the shaft 10 through the circular gear wheels 25 and 26, and the elliptical or cam shaped gear wheels 27 and 28 which are carried on fixed axles 29. The wheel 28 gives motion to a crank 80 pin 30 upon a disk, crank or wheel 60 which is connected to the lever 22 by a link 31, this gearing being so designed and arranged that the shuttles make a back to front, or front to back traverse for each up and down 85 movement of the central frame and so that the shuttles work in unison with the movement of the central frame.

In the modification shown in Fig. 7 the shuttle guides are circular arcs struck from 90 a convenient center and the shape of the shuttle is modified accordingly. The shuttles are traversed by pinions 18 on the shafts 17 by the means and in the manner substantially as herein before described with reference to the straight shuttle guides shown in Fig. 3.

The shuttle 16, Fig. 5, for use in the improved loom is preferably in the form of an approximately triangular frame the base of 100 which is provided with gear teeth 32^a which engage with the teeth of the shuttle driving pinions 18. The shuttle thread *a* is wound upon a thin spool or bobbin 32 which is fitted to rotate on a fixed axle 33 which is 105 at right angles to the length of the shuttle and is carried by the cross bar 33^a, the shuttle being held upon the axle by a spring

wire clip 33^b. There is also a brake lever 34 which is pressed upon the circumference of the thread of the spool by a spring 35, and a spring 36 by which the slack of the thread 5 is taken up and which in conjunction with the brake acts to tension the thread drawn from the shuttle.

The threads *b* for each piece of tape are wound upon separate bobbins 38 and each 10 bobbin is provided with an adjustable brake or tensioning lever 39. The threads pass over guide rods 40 to the tensioning rods 41 and upward to a fixed wire net thread guide 42. From this guide the threads pass up- 15 ward to thin steel bars 43 which are suitably perforated for the threads and each bar carries one thread for each piece of tape to be made. The bars 43 extend the full width of the machine and for plain tapes the bars are 20 divided into odd and even numbered sets and are, or may be, actuated to form the shed by any suitable arrangement of cam mechanism, but for the manufacture of fancy or patterned goods, the bars 43 are 25 actuated to select the threads by a jacquard or other similar pattern mechanism.

The reed 44 is attached to the inner ends of the shuttle guide brackets 15 and the work *c*, as it is made is taken up by rollers 30 45 the surfaces of which are suitably roughened. These rollers are positively driven by a worm 46 and worm wheels 47 on the ends of the axles carrying the rollers, and preferably also one or both of the rollers are connected to their axles by a ratchet or other clutch 48, Fig. 6, so that any piece of work can be drawn backward when required. The woven tapes pass over a roller 49, which may if desired be rotated and around guide rods 40 59 and 51, and at the rod 51 the tapes are divided, the odd, or even numbered, tapes being wound up on the front bobbins or creels 53, and the even, or odd numbered tapes, being wound up by the back bobbins or creels 45 53 and both sets of bobbins or creels are frictionally driven by cords 54 from pulleys or rollers 55.

In a modification of the work take-up mechanism particularly suitable for narrow 50 widths the rollers 45 are loosely mounted on their axles and the roller 49 is positively driven for taking up the work. When the rollers 45 are positively driven, as shown in the drawings, the roller 49 and the rod 59 55 may be dispensed with and the tapes be passed from the rollers 45 direct to the rod 51 where they are divided.

The drawings illustrate the construction of a loom in which the reed 44, the shuttles

16, and the shuttle guiding and actuating 60 mechanisms are carried by a vertically moving central frame and also arrangements of mechanisms for actuating the central frame and the shuttles. These parts are so timed relatively to each other that when the reed 65 is in its lowest position the shuttles are in the central position half way through the shed, and soon after the shuttles have passed this position the reed commences to rise to its beat up position. After the completion 70 of the beat up motion the reed commences its downward movement and during such movement the sheds are changed and the shuttles commence their return traverse and reach their central position at approximately 75 the same time as the reed completes its downward stroke.

We claim:—

1. In a narrow ware loom the combination 80 of a central frame, the shuttles and shuttle driving mechanisms carried by such frame, end guides for the frame, balancing springs for the central frame, a rotating crank for reciprocating the frame, and links and levers between the central frame and the crank designed and arranged to give a short period 85 of rest to the frame when such frame is in its lowest position substantially as herein described.

2. In a narrow ware loom the combination 90 of a stationary supporting frame, a movable frame supported in the stationary frame, the shuttles, gear teeth on the shuttles, toothed pinions for driving the shuttles, shafts carrying such toothed pinions supported in the movable frame, a toothed quadrant for actuating the shafts pivotally united with the movable frame, a slotted lever for driving the quadrant pivotally supported in the stationary frame, and crank 95 and elliptical toothed gear wheels for operating the slotted lever substantially as herein described.

3. In a narrow ware loom the combination 105 of a vertically reciprocating frame carrying the shuttles and the shuttle actuating mechanisms, guide rods carried by the frame, the weight balancing springs, fixed guides for the frame with which the said guide rods co-operate, and a crank, levers and links for 110 reciprocating the frame substantially as herein described.

ARTHUR EDWARD STROUD.
HAROLD FREDERICK SOAR.
